UNITED STATES PATENT OFFICE.

WILLIAM M. SHEEHAN, OF ST. LOUIS, MISSOURI, ASSIGNOR TO COMMONWEALTH STEEL COMPANY, OF ST. LOUIS, MISSOURI, A CORPORATION OF NEW JERSEY.

UNDERFRAME FOR ORE CARS.

Application filed July 21, 1922. Serial No. 576,527.

Figure 1 is a plan view of my improved underframe for ore cars.

Figure 2 is an end elevational view.

Figure 3 is a side elevational view.

Figure 4 is a vertical sectional view on line 4-4 of Figure 1.

Figure 5 is a vertical sectional view on line 5-5 of Figure 1.

Figure 6 is a vertical sectional view on line 6-6 of Figure 1.

Figure 7 is a vertical sectional view on line 7-7 of Figure 1.

This invention relates to a new and useful improvement in underframes for ore cars and is of that type shown in the copending application filed by me on the 21st day of July, 1922, Serial No. 576,526.

The object of my present invention is to construct an underframe for ore cars in the form of a single casting, preferably cast steel, which underframe is characterized by an opening in the center, the end walls of said opening being curved and obliquely disposed so as to form the lower portion of the hopper. The side walls of this opening are preferably formed by obliquely disposed overhanging eaves or ledges under which are arranged perforated lugs for the attachment of the hopper doors (not shown). By this construction, the hinges by which the hopper doors are secured to the underframe are protected from the lading and any water, which usually seeps through the lading, will be shed into the hopper opening to one side of the hinges so that said hinges are not liable to freeze in cold weather.

My improved cast steel underframe, other than the peculiar construction forming the hopper opening, has side sills, draft sills, end platforms, and other parts containing novel details all of which are hereinafter more fully set forth and claimed.

That part of the underframe casting which forms the end sill, preferably includes a vertical web 1, the middle portion of which is relatively deep and is provided with a recess 2 for the reception of the drawbar, this portion of the web constituting a wall which forms substantially the well known "dead block".

Shallow portions 3 of the end sill extend to the sides of the car and are there integrally connected with the web flanges 4 of the car underframe. A horizontal web

7 forms a platform integrally uniting the end sill flanges 4, side sills and draft sills 6 which may be provided with the usual stops and lugs for draft rigging. The vertical webs of these draft sills diverge slightly at their inner ends and are connected to an obliquely disposed curved web 8 forming a part of the end wall of the hopper.

Reinforcing webs 9 are preferably spaced from the wall 8 and, as shown, (in Figure 7), the bottom flange of one of these reinforcing webs 9 may be extended outwardly and provided with a center bearing 10 whereby a swiveling truck may be employed with this type of underframe.

The ends of the deep portion 1 of the end sill web constituting the dead-block are conjoined to diverging vertical disposed webs 11 which (see Figure 1) throughout the major portion of the length of the underframe run parallel to each other and to reinforcing flanges 4 before mentioned and constitute the webs of the car side sills. These webs 11 throughout the major portion of their length (see Figures 3, 5, and 7), are provided with outwardly extending bottom flanges 12, and with the top flanges 13 which are preferably flush with the horizontal web 7 constituting end platforms. At points intermediate their lengths, the side sills composing the parts 11, 12, and 13 are reinforced by transversely disposed webs 15, and the horizontal flange 13 is provided with a finishing surface 16 to which the knee braces (not shown) for supporting the side walls of the hopper may be secured.

The inner edges of the horizontal flanges 13, at the sides of the hopper opening, are provided with obliquely disposed eave extensions 17 constituting the water shed for the hinge lugs 18 (see Figures 1, 4, and 5).

The obliquely disposed end wall 8 is preferably enlarged at its lower end, as shown in Figure 4, and provided with a downwardly extending lug 8^a for the attachment of the hopper door operating machine (not shown). The horizontal webs 7 constituting the end platforms may be lightened by openings, as indicated in Figure 1, and these platforms are preferably recessed, as at 7^a, so as to provide a handhold opening bridged by a grab iron (not shown). The finishing surfaces 7^b extend above the horizontal webs 7, and in order to provide bearings for truck

frames whose side members are pivotally connected to the underframe, I preferably arrange a web 19 parallel to the diagonally disposed web 11 (see Figures 1 and 6) which 5 webs 11 and 19 together with their transversely disposed reinforcing webs 20 constitute a box-like structure for carrying a horizontally disposed bearing plate 21. This bearing plate is designed to provide 10 support for truck side frames of the type shown in United States Letters Patent No. 1,358,016, granted to H. M. Pflager on the 9th day of November, 1920.

When the underframe is mounted upon 15 swiveling trucks, suitable side bearing projections may be provided as illustrated at 22, in Figure 7.

Other modifications of my invention may 20 be made without departing from the spirit 25 thereof as expressed in the following claims.

What I claim is:—

1. A cast steel underframe having a centrally arranged hopper opening, the end walls of which are curved and obliquely disposed.
2. A cast steel underframe having a central hopper opening the side walls of which are inclined to provide a water and lading shed, said underframe having hinged members located under said inclined shedding walls.
3. In a cast steel underframe, an integral bolster, end sill and side sills, the latter converging towards each other from the bolster to the end sill.
4. A cast steel underframe having side and end sill members and horizontal flanges at the ends of said members constituting end platforms having raised portions forming finishing surfaces.

5. A cast steel underframe having spaced end sills, side sills connecting said end sills, horizontal flanges extending inwardly from said end and side sills and forming platforms at the ends of the car, and draft sills integral with said platform forming flanges.

6. A cast steel underframe having side and end sill members, the horizontal flanges thereof at the ends of the underframe forming end platforms, and draft sills integral with said platform flanges, the vertical webs of said draft sill members diverging at their inner ends.

7. A cast steel underframe having horizontal flanges constituting end platforms, and a centrally located hopper opening, the side walls of which hopper opening are obliquely disposed, vertical webs constituting side sill members on each side of said opening and vertical webs constituting draft sills extending from the ends of the underframe to the end sills of said hopper opening.

8. A cast steel underframe having side sill members composed of vertical and horizontal flanges, transversely disposed rein-

forcing webs and integral finishing surfaces of the top surfaces of the horizontal flanges of said side sill members.

9. A cast steel underframe composed of side and end sills, each of said sill members 70 being made up in part of vertically and horizontally disposed webs or flanges, one of the vertical flanges of the side sill member being provided with a jog or bend forming a handhold recess designed to be bridged by 75 a grab iron.

10. A cast steel underframe including side sill-members whose vertical webs converge towards each other at the ends of the underframe and horizontally disposed 80 bearing plates for truck side frames integrally connected to the vertical webs of said side sill members.

11. A cast steel underframe having horizontally disposed webs forming end platforms, horizontally-disposed truck pivotal bearing plates between the center and sides of the underframe spaced from said platform webs and supported in position by vertically disposed webs, vertically disposed webs forming reinforcements for said horizontally disposed webs said truck bearing plates being integrally connected with said reinforcing webs.

12. A cast steel underframe having vertical webs and horizontally disposed webs forming sill members, horizontally disposed plates constituting pivotal connections for truck side frames and angularly disposed vertical webs integrally connected therewith 95 and providing a boxlike support therefor.

13. In a cast steel underframe, an integral bolster, end sill and side sills, said end sill having a vertical web which is relatively deep throughout its central portion and relative shallow throughout its side portions, said side sills converging towards each other from the bolster to the end sill and there merging with the deep central portion of said end sill.

14. In a cast steel underframe, an integral bolster, end sill and side sills, said end sill having a relatively deep central portion and relatively shallow side portions each of said side sills having a vertical web and horizontal web flange at its outer edge, the vertical webs of said side sills converging towards each other between said bolster and end sill and there converging with the deep portion of the latter, and the flange edges of the side sills extending longitudinally to and merging with the shallow side portions of the end sill.

15. A cast steel underframe for hopper cars comprising spaced sills at the sides of the hopper opening, a bolster at the end of the hopper opening, an end sill, said side sills including vertical webs which converge towards each other between the bolster and end sill and merge with the latter.

16. A cast steel underframe having side and end sill members, horizontal flanges on said members extending inwardly therefrom, integral draft sills having horizontal flanges extending outwardly therefrom, said flanges forming end platforms for a car mounted on the underframe.
17. A cast underframe including integral side sill and end sill members each having vertical webs and horizontal flanges, said webs being of unequal depth and said flanges merging to provide platform forming surfaces extending over the wheels of a truck on which the underframe is mounted.
18. A cast underframe having vertical side and end sill forming webs and intermediate vertical webs, center and side bearings integrally connected with said web, and horizontal flanges extending inwardly from said end sill webs, said flanges constituting end platforms which are spaced from said center and side bearings by said intermediate webs.

In testimony whereof I hereunto affix my signature this 12 day of July, 1922.

WILLIAM M. SHEEHAN.
